(57) **CLAIM**

The ornamental design for a campfire working tool, as shown.

DESCRIPTION

FIG. 1 is a perspective view of the campfire working tool. FIG. 2 is a side view of the tool of FIG. 1.

FIG. 3 is an opposite view of the tool of FIG. 1.

FIG. 4 is a top view of the tool of FIG. 1.

FIG. 5 is a bottom view of the tool of FIG. 1.

FIG. 6 is a front view of the tool of FIG. 1; and, FIG. 7 is a rear view of the tool of FIG. 1.

The broken lines depict portions of the campfire working tool in which the design is embodied that are not considered part of the claimed design.
